UNITED STATES PATENT OFFICE.

CARL HERMANN CHRISTEL, OF BERLIN, GERMANY, ASSIGNOR TO MERGENTHALER LINOTYPE COMPANY, A CORPORATION OF NEW YORK.

LINOTYPE-MACHINE.

1,095,309.

Specification of Letters Patent.

Patented May 5, 1914.

Application filed November 15, 1909. Serial No. 528,222.

To all whom it may concern:

Be it known that I, CARL HERMANN CHRISTEL, a subject of the Emperor of Germany, and resident of Berlin, Germany, 5 have invented certain new and useful Improvements in Linotype-Machines, of which the following is a specification.

In linotype machines arranged for matrices with two or more superposed intaglio letters the slide or second elevator or other device which presents the composed line of 10 matrices and space-bars to the mold or mold-wheel for the casting of the linotype may be provided with either one or several horizontal ledges, on which the respective matrices, if raised, are made to slide and to rest with their lower rear ears or lugs as shown, 15 for instance in Letters Patent No. 547,633 to P. T. Dodge. This arrangement presents the defect, that the alinement of the letters 20 in the cast line when cast from raised matrices is soon rendered irregular, as the bottom faces of the lower ears or lugs of the matrices become worn away much more rapidly than the other supporting faces of 25 the matrices, since each matrix constantly and repeatedly drops and strikes with its lower ears or lugs various machine parts and the other matrices and when raised it is 30 exclusively guided by its lower ears nearly during its entire passage through the machine. The matrices with two or more superposed intaglio letters are supported on the bottom faces of their upper ears or lugs, 35 like ordinary matrices with single intaglio letters, only in case their upper or uppermost intaglio letters are used for casting the linotypes. When the lower intaglio letters are to be used for casting the linotypes, 40 of course the respective matrices require to be raised into their upper or any of their upper positions, so that the bottom faces of their upper ears remain at a height above the guiding shoulders of the slide or 45 second elevator or other device, and consequently the respective ledge or ledges in the device will have to engage beneath the lower rear ears of the matrices for supporting and guiding the latter. It is thus obvious, that 50 after the bottom faces of the lower ears have been more or less worn away the several letters in the linotype cast from raised matrices will no longer be alined, they being more or less lowered in proportion to the

wear of the bottom faces of the lower rear 55 lugs of the respective matrices. As the intaglio letters in the matrices representing different fonts are used differently, one font being employed much more than the other or any of the others, it follows, that 60 the respective matrices are not used uniformly and consequently their lower rear lugs will be irregularly worn away. From this reason also the alinement of the letters 65 in the cast linotypes can not be maintained any longer.

My invention relates to improvements in 70 linotype machines of the class described, whereby the said defect is avoided in a most simple and certain manner.

One improvement consists in providing 75 each matrix having more than one intaglio letter with one or several recesses above its lower ear or lug in the side edge opposite to the intaglio letters.

Another improvement consists in reducing 80 the breadth of the space-bars between the guiding rails either for a part only or for the whole of their length beneath their upper projecting arms.

A third improvement consists in so arranging 85 the single or several horizontal ledges in the slide or second elevator or other device as to enable it or them to engage either in the said recesses of the matrices or beneath not only the bottom of their lower rear ears but also a part of their bottom proper within the plane of the edges of the matrices. In other words the horizontal ledge or ledges is or are enabled to coöperate 90 with parts of the matrices which are practically not subjected to any wear and tear during the passage of the matrices through the machine.

I will now proceed to describe my invention 95 with reference to the accompanying drawing, in which—

Figure 1 is a vertical cross section through a part of a mold-wheel with the mold and through the slide or second elevator or other 100 device in a plane adjacent a matrix occupying its lower position, while another matrix behind the same occupies its upper position, all of the matrices being assumed to be provided with only two superposed intaglio 105 letters, Fig. 2 is a similar section in another plane adjacent a matrix occupying its upper position, while another matrix behind the

same occupies its lower position, Fig. 3 shows one of the matrices, Fig. 4 shows a space-bar, the recess of which extends over most of its length, Fig. 4^a shows a modified space-bar, the recess of which only extends over a part of its length, and Fig. 4^b shows a further modification of the space-bar, in which the breadth is reduced for the whole length up to one projecting arm.

16 Similar letters of reference refer to similar parts throughout the several views.

17 *a* denotes the mold-wheel, *b* the mold, and *c* the slide or second elevator or other device for presenting line of matrices to the mold. The latter is provided with the known shoulders *h h* for supporting and guiding the upper ears or lug *g¹ g²* (Fig. 3) of the matrices *g* when they occupy their normal lower position (Fig. 1), their faces 20 *g³ g³* resting and sliding on the shoulders *h h*. In this case their lower rear ears or lugs *g⁴* engage beneath the ledge *d*, which serves for supporting and guiding these ears *g⁴*, if the matrices *g* are raised into their 25 upper position (Fig. 2).

18 According to my invention all of the matrices *g* are each provided with a recess *i* (Fig. 3) immediately above the lower rear ear *g⁴*, and in consequence of this the ledge 30 *d* is so much extended as to be capable of engaging in these recesses *i* of the matrices *g*. The space-bars *e* are therefore reduced in their breadth, they being provided in the rear (left in Figs. 4 and 4^a) side edge with 35 a recess *k*, which may extend either over a part of the length (Fig. 4^a), or over most of the length (Fig. 4), or over the whole length up to one projecting arm *f* (Fig. 4^b). Thus the space-bars are during the justification 40 of the composed line permitted to freely move vertically past the extended ledge *d*. Some known mechanism is employed for raising the respective matrices *g* into their upper position, before they are 45 pushed into the device *c*.

19 It will be evident, that the extended ledge *d* engaging in the recess *i* of any matrix *g* which is not raised will support the latter on the upper surface of the recess *i* (Fig. 50 1). If however any matrix *g* is raised, the extended ledge *d* will engage beneath the lower rear ear *g⁴* and also on the part *g²* (Fig. 3) of its bottom proper, within the plane of the edge of the matrix, which part 55 is not subjected to any wear and tear. Thus the extended ledge *d* will come in contact with each matrix *g* only on either of two faces which practically do not undergo any wear and tear during the passage of the 60 matrix through the whole machine with the exception of the device *c*. Thereby the alignment of the several letters in the cast linotypes is guaranteed for a much longer time than hitherto.

65 It is evident, that the invention can be

applied to existing linotype machines, as it is only necessary to provide all of the matrices with the recess *i*, to reduce the breadth of the space-bars for a part or for the whole of their length up to their projecting arms *f*, 70 and to provide the slide or second elevator or other device *c* with an extension of its ledge in any known manner, for example by taking off a part of the height of the ledge *d* and attaching to the device *c* a plate 75 of the required width.

It is further evident, that the invention can also be partially applied to existing linotype machines in which ordinary matrices with single intaglio letters are employed, as it is possible to provide the device *c* with a detachable plate in place of the lower part with the ledge *d*. In case the lower ears of the matrices are worn away, the matrices need then not be cast away, 80 since the detachable plate can be replaced by another one of a greater width, which engages beneath a part (*g²* in Fig. 3) of the bottom proper of the matrices that is practically not subjected to any wear and tear. 85 In this manner the life of the matrices can be further lengthened, until their intaglio letters are worn off.

90 In case the matrices are provided with more than two superposed intaglio letters, of course it will be necessary to provide them with more than one recess *i* and this in a manner which is obvious to any expert. For example matrices with three superposed intaglio letters will require to have each two superposed recesses *i* above the lower rear ear *g⁴*, and the slide *c* or its equivalent will require to have two superposed horizontal ledges *d*.

95 It is essential that the matrices and space bars for each line should be securely clamped together at the mold and also that they should be accurately and closely pressed or clamped against the mold, in order that no metal may escape between or around the matrices when the pump is operated. The ledge *d* is made to fit the notch of each matrix and to extend exactly to the bottom of the notch when the matrix is in casting 100 position. When thus proportioned the ledge operates as a part of the clamping devices to press the matrices firmly and uniformly against the mold. The space bars are required to be not greater in width than the 105 distance from the ledge to the plane of the face of the mold in order that they may be pushed up during the justification of the line. On the other hand the width of the space bars should be equal to the width of the bodies of the matrices at the notches *i*, that is, their width should be equal to the 110 distance from the bottom of the notch *i* to the opposite side of the matrix. When thus constructed the ledge *d* will press 115 equally upon the space bars and matrices 120 125 130

and hold them uniformly against the mold. The ledge *d* therefore serves to sustain the matrices at the proper elevations when presenting them to the mold and also to assist in pressing the matrices and space bars uniformly against the mold to prevent any escape of metal along the inner face of the matrix line.

5 The matrices and space bars described herein are claimed, respectively, in divisional applications, Serial No. 694,358, filed May 1, 1912, and Serial No. 785,316, filed August 18, 1913.

I claim:

15 1. In a linotype machine, the combination with a series of matrices, each provided with an ear at its lower end, of a device for presenting matrices to the mold having a ledge extending inward beyond the plane of the 20 edges of the matrices and adapted to support the matrices by contact with the portion of the lower ends thereof within said plane, for the purpose set forth.

25 2. In a linotype machine, the combination with a series of matrices, each provided with an ear at its lower end, of a device for presenting matrices to the mold having a ledge extending inward beyond the plane of the 30 edges of the matrices and adapted to support the matrices by contact with the portion of the lower ends thereof within said plane, each matrix having a recess above the ear to receive the ledge when the matrix is in its lower position, for the purpose set forth.

35 3. In a linotype machine, the combination with a series of matrices, each provided with an ear at its lower end and each having a plurality of character indentations, of a device for presenting matrices to the mold 40 having a ledge extending inward beyond the plane of the edges of the matrices and adapted to support the matrices by contact with the portion of the lower ends thereof within said plane, each matrix having a recess above the ear to receive the ledge when the matrix is in its lower position, for the purpose set forth.

45 4. In a linotype machine, the combination of a device for presenting matrices to the 50 mold, a series of matrices, and a series of space bars, said device being provided with a ledge projecting inward beyond the plane of the adjacent edges of the assembled matrices and adapted to support said matrices 55 by contact with portions of their lower ends within said plane, and the space bars having recesses in their edges to permit them to clear said ledge, for the purpose set forth.

5. In a linotype machine, a matrix having 60 a plurality of character indentations in one edge and a recess in its opposite edge, and ears at its upper and lower ends extending beyond the plane of said edges, in combination with a mold, and a device for presenting matrices to the mold, said device having

a ledge extending inward beyond the plane of the adjacent edge of the matrix, the said ledge being adapted either to enter said recess to support the matrix in the lower position or to support the matrix in an upper 70 position by contact with a portion of the lower edge of the matrix within the said plane, for the purpose set forth.

6. In a linotype machine, the combination with matrices each having a body with parallel edges and ears projecting beyond the body on opposite sides thereof, a type impression in one edge of the body and a notch in the opposite edge extending within the general line of the edge, and space bars each 80 reduced in width for a portion of its length to the width of the matrices at the notches, of means for supporting said matrices and space bars in an assembled line.

7. In a linotype machine, the combination with a series of matrices each having a body with parallel edges and ears projecting beyond the body on opposite sides thereof, a type impression in one edge of the body and a notch in the opposite edge near the 90 lower part thereof and extending within the general line of the edge, and a series of space bars each having its lower part reduced in width to the width of the matrices at the notches and its upper part 95 conforming in width to the full width of the matrices, of means for supporting said matrices and space bars in an assembled line.

8. In a linotype machine, the combination with a series of matrices having upper and lower ears on opposite sides and a body intermediate the upper and lower ears, each matrix having a type impression in one edge of its body and a notch or recess in the opposite edge between the ears and extending 100 within the general line of the edge, and space bars having ears corresponding to the upper ears of the matrices, the portions of said space bars which coöperate with the notched portions of the matrices being reduced in width to the width of the matrices at the notches, of means for supporting 105 said matrices and space bars in an assembled line.

9. In a linotype machine, the combination 115 with a mold, of a device for sustaining a plurality of matrices and space bars and presenting them to the mold, the wall of said device opposite the mold having a ledge extending inward beyond the body 120 line of the matrices, a plurality of matrices each having a body with parallel edges and ears projecting beyond the body on opposite sides thereof, and a notch in its body portion adapted to receive said ledge, and a 125 plurality of space bars each having a portion reduced in width to the width of the matrices at the notches, whereby the ledge when arranged in the notches of the matrices is adapted to simultaneously clamp 130

the matrices and space bars against the mold.

10. In a linotype machine, the combination of plural letter matrices formed with 5 projecting ears, and means for supporting the matrices, the said supporting means being extended sufficiently to engage the matrices not only at their ears but also at a point beyond the ears, and the matrices being further formed with notches to receive 10 the said extended supporting means when located at a different level.

11. In a linotype machine, the combination of matrices formed with projecting 15 ears, the mold, and the first elevator provided with means for supporting the matrices, the said supporting means being extended sufficiently to engage the matrices not only at their ears but also at a point 20 beyond the ears.

12. In a linotype machine, the combination of plural letter matrices formed with projecting ears, the mold, and the first elevator provided with means for supporting 25 the matrices, the said supporting means being extended sufficiently to engage the matrices not only at their ears but also at a point beyond the ears, and the said matrices being further formed with notches to re-

ceive the said extended supporting means 30 when located at a different level.

13. In a linotype machine, the assembled line comprising matrices and spacers, the said spacers having a body width less than that of the matrices, combined with a mold 35 and means to hold the assembled line in operative relation thereto.

14. In a linotype machine, the assembled line comprising matrices and spacers, the said spacers having a body width less than 40 that of the matrices, combined with a mold and means for supporting the matrices and for forcing the spacers against the mold.

15. In a linotype machine, the assembled line comprising matrices and spacers, the 45 said spacers having a body width less than that of the matrices, combined with the mold, and the first elevator, the elevator being provided with a rib to support the matrices vertically and to force the spacers 50 against the mold.

In testimony whereof I affix my signature in presence of two witnesses.

CARL HERMANN CHRISTEL.
